UNITED STATES PATENT OFFICE.

ALICE SMOLIN, OF MANAYUNK, PENNSYLVANIA.

RING BUTTON.

Application filed December 8, 1927. Serial No. 238,537.

My invention relates to new and useful improvements in a button and the process of making the same, and has for its primary object to provide a simple and effective device of this character which will be neat and unique in appearance and one that can be made to correspond exactly with the garment on which it is to be used.

Another object of my invention is to make a button by a process which consists in wrapping a thread about a ring in one direction, then wrapping another or the same thread about the ring in another direction at right angles to the first mentioned thread, then securing said threads at their points of crossing, then separating the strands of threads so that they radiate from the center fastening or tie, and lastly stitching the threads together along the inner circumference of the ring.

A further object of my invention is to provide a means by which the center of the structure may be reinforced.

With these ends in view, this invention consists in the details of construction and combination of elements hereinafter set forth and then specifically designated by the claims.

In order that those skilled in the art to which this invention appertains may understand how to use and make the same, I will describe its construction in detail, referring by numerals to the accompanying drawings forming a part of this application, in which:—

Fig. 1 is a face view of the ring forming the core of the button.

Fig. 2 is a similar view illustrating the first steps in the manufacture of the button.

Fig. 3 is a face view of the completed button.

Fig. 4 is a cross-section of Fig. 3.

Fig. 5 is an enlarged sectional view of the button showing a method of reinforcing the same.

Fig. 6 is a similar view of the ring which can be used with a reinforced button.

In carrying out my invention as herein embodied, 7 represents a ring of suitable diameter and of any desirable material, either solid as shown in Fig. 4 or hollow as illustrated in Figs. 5 and 6 and designated by the numeral 7. This ring, if found desirable, whether hollow or solid, may be provided with a circular crack, in the form of a groove or slot, running entirely around the

interior diameter as exemplified in Figs. 5 and 6 where the slot is shown at 8.

In the simplest form of the device I use a solid ring, such as shown at 7, and wrap or wind a thread 9 around one diameter of the ring to provide a number of coils with the strands of said thread disposed on opposite sides of the ring. Wherever thread is referred to it is used in its broadest sense so as to include sewing thread, string, wire or other quite long but relatively thin flexible material. Next, another wrapping of thread 10 is placed on the ring in some position that will be crosswise of the thread 9 and the position of the second thread is preferably at substantially right angles to the first one as shown in Fig. 2.

After the threads have been wrapped or wound as described they are fastened or secured at their points of crossing by thread 11 which is passed around all of the crossing strands of the threads 9 and 10 in two directions from the corners of the thread bands 9 and 10 diagonally to said bands thus forming a "cross", Fig. 2. The thread 11 is drawn sufficiently taut to bring the bands of threads 9 and 10 close together at their points of crossing.

After the thread bands have been fastened together to prevent accidental slipping of the threads composing said bands and to maintain the center, the strands of said threads are moved along the outer circumference of the ring until said strands are in radial positions as shown in Fig. 3 where the thread strands are designated by the numeral 12.

To complete the button the radially arranged thread strands are stitched together around the inner circumference of the ring by stitches 13 thus producing a web across or within the open space of the ring.

Where the thread for making the button is of weak or fragile material it is possible to reinforce the button web by placing a disc 14, of material that can be readily penetrated by a needle, such as textile fabric, rubber, card board and celluloid, within the open space of the ring prior to wrapping or winding the threads thereon to produce the thread bands 9 and 10, and if found desirable the edges of the disc may be inserted in the crack 8. If the ring is of slotted hollow construction, when the thread strands are stitched down the ring will clamp the disc as will be obvious.

Of course I do not wish to be limited to the exact details of construction as herein shown, as these may be varied within the limits of the appended claims without departing from the spirit of my invention.

Having thus fully described my invention, what I claim as new and useful is:—

1. A button comprising a ring, threads disposed about said ring and radiating from the center thereof, means to secure said threads midway of their ends and stitches holding the threads together on opposite sides of the ring about the inner circumference.
- 15 2. A button comprising a ring, two sets of threads wound diametrically about the ring, one set outside of the other, the strands of said threads on both sides of the ring radiating from the center of said ring, means to secure the threads together at their centers where one set crosses the other set, and stitches securing said threads together about the inner circumference of the ring.
- 20 3. The structure set forth in claim 2, in

combination with a reinforcing disc located 25 between the strands of the sets of threads on opposite sides of the ring.

4. The process of making a button which consists in winding two bands of threads about a ring on two different diameters of 30 the latter, tying said bands of threads together at their point of crossing, separating the strands of said threads and positioning them about the ring so that they radiate from the point of tying, and stitching 35 through said threads about the inner circumference of the ring.

5. A button comprising a ring, bands of threads wound about two different diameters of said ring, means to tie the thread 40 bands at the center of the ring, the threads of said bands being separable until all radiate from the point of tying, and means to fix said threads in their separated positions.

In testimony whereof, I have hereunto 45 affixed my signature.

ALICE SMOLIN.
